(57) CLAIM

The ornamental design for a device for storing and dispensing a medicament, as shown and described.

DESCRIPTION

FIG. 1 is a perspective view of the device for storing and dispensing a medicament.

FIG. 2 is a top plan view of the device for storing and dispensing a medicament illustrated in FIG. 1;

FIG. 3 is a bottom view of the device for storing and dispensing a medicament illustrated in FIG. 1;

FIG. 4 is a left side view of the device for storing and dispensing a medicament illustrated in FIG. 1;

FIG. 5 is a right side view of the device for storing and dispensing a medicament illustrated in FIG. 1;

FIG. 6 is a front end view of the device for storing and dispensing a medicament illustrated in FIG. 1; and,

FIG. 7 is a rear end view of the device for storing and dispensing a medicament illustrated in FIG. 1.

The broken lines immediately adjacent the shaded areas represent the bounds of the claimed design while all other broken lines represent portions of the article; the broken lines form no part of the claimed design.

1 Claim, 5 Drawing Sheets
